US00D692419S

(12) **United States Design Patent**
Rayner

(10) **Patent No.:** **US D692,419 S**
(45) **Date of Patent:** **** Oct. 29, 2013**

(54) **CASE FOR AN ELECTRONIC DEVICE**

(75) Inventor: **Gary Rayner**, Lemon Grove, CA (US)

(73) Assignee: **TreeFrog Developments, Inc.**, San Diego, CA (US)

(**) Term: **14 Years**

(21) Appl. No.: **29/432,150**

(22) Filed: **Sep. 13, 2012**

(51) **LOC (9) Cl.** **14-03**

(52) **U.S. Cl.**

USPC **D14/250**

(58) **Field of Classification Search**

CLAIM

The ornamental design for a case for an electronic device, as shown and described.

DESCRIPTION

FIG. 1 is a front view of the case for an electronic device. FIG. 2 is a rear view of the case for an electronic device. FIG. 3 is a bottom view of the case for an electronic device. FIG. 4 is a top view of the case for an electronic device. FIG. 5 is a left side view of the case for an electronic device. FIG. 6 is a right side view of the case for an electronic device. FIG. 7 is a rear and right side perspective view of the case for an electronic device; and, FIG. 8 is a front and right side perspective view of the case for an electronic device.

The dark/light diagonal contrast shown on the front of the case in FIGS. 1 and 8 depicts a shiny surface consisting of a central rectangular transparent region and a surrounding shiny opaque region. The dark/light diagonal contrast shown on the rear of the case in FIGS. 2 and 7 depicts a transparent surface. Surfaces that underlie the transparent surfaces are not part of the claimed design.

1 Claim, 7 Drawing Sheets
